UNITED STATES PATENT OFFICE

NICKOLAS JOSEPH DZIEDZIC AND HARRY HENRY MCKEE, OF CHICAGO, ILLINOIS,
ASSIGNORS, BY MESNE ASSIGNMENTS, TO INDUSTRIAL PATENTS CORPORATION,
OF CHICAGO, ILLINOIS, A CORPORATION OF DELAWARE

SLICING MACHINE

Application filed October 2, 1930. Serial No. 485,848.

Our invention relates to a slicing machine, and more especially to a feed mechanism for meat slicing machines.

One of the objects of our invention is to provide a continuous feed mechanism of the conveyor type, in order to provide a positive feeding means which may be operated continuously or intermittently.

With these objects in view, the invention consists in the novel construction and arrangement of parts hereinafter described and illustrated in the accompanying drawings, and particularly pointed out in the appended claims, it being understood that various changes in the form, proportions, size and details of construction may be made within the scope of the claims without departing from the spirit or sacrificing any of the advantages of the invention.

20 Referring now to the drawings:

Figure 1 is a top elevation of the feeding mechanism.

Figure 2 is a longitudinal section through 2-2 of Figure 1, showing the driving means in elevation.

Figure 3 is a section through 3-3 of Figure 1, partly in elevation.

Figure 4 and Figure 5 are sectional views through 4-4 of Figure 1, Figure 4 showing a belt and Figure 5 showing an endless chain arrangement, either of which may be used.

Figure 6 is a longitudinal view, partly in section, showing a single bar mounted on a belt as in Figure 4.

35 Figure 7 is an end view in section of Figure 6.

Figure 8 is a longitudinal view, partly in section, of a single bar mounted on an endless chain as in Figure 5.

40 Figure 9 is an end view, partly in section, of the bar shown in Figure 8.

The accompanying drawings disclose a practical embodiment of the invention. In the drawings similar reference numerals indicate corresponding views in the several figures.

An angle iron frame —1— supports the mechanism. An apron 2, consisting of a plurality of metal bars as 3, appropriately mounted, passes over pairs of wheels, one of

each pair of wheels being shown in Figure 2 as 4 and 5. The wheels are axially mounted on shafts 6 and 7, shaft 7 being journaled to the angle iron frame 1 at 8 and 9, shaft 6 being journaled to the angle iron frame 1 at 10 and 11, which are not shown inasmuch as these points come below 19 and 20 in Figure 1. An endless conveyor 12, consisting of a plurality of metal bars 3, appropriately mounted, passes over pairs of wheels, one of each pair, wheel 13 and wheel 14, being shown in Figure 2. Each pair of wheels is axially mounted upon a shaft, as 15 and 16, shaft 16 being journaled to the angle iron frame at 17 and 18, shaft 15 being journaled to the angle iron frame at 19 and 20. Power is supplied from motor 21 through belt 22 and shaft 23 to knife 24, to cut the product as it is forced through opening 25. Shaft 23 is mounted in bushings 26 and 27, being carried through at each end. Gear 28 is mounted on shaft 23, meshing with gear 29, mounted on shaft 30. Shaft 30 is axially mounted at 31, wheel 32 being mounted at the end of shaft 30, driving wheel 33 by means of belt 34, wheel 33 being mounted on shaft 35, on which is also mounted wheels 36 and 37. Belt 38 passes over wheel 36, driving wheel 39, which is mounted on shaft 6. Wheel 37, mounted on shaft 35, drives wheel 40 by belt 41. Wheel 40 is mounted on shaft 15. When power is applied, the conveyors move in the direction of the arrows, as shown in Figure 2.

Where product is being sliced which is not of uniform thickness, apron 12 may be adjustably mounted, either with a fixed adjustment as where the variation is between lots rather than between individual pieces of meat such as bacon sides, or mounted with a spring adjustment so as to compensate for variation within prescribed limits.

The bars which make up the conveyor are preferably square in cross section, with one angle directed toward the product in order that the product may be firmly gripped. The bars are triangular in cross section at the end, to permit of easy mounting upon a belt or chain, which construction will be noted in Figures 6, 7, 8 and 9.

We claim:

1. In a slicing machine, a frame, a set of lower transversely extending shafts for supporting and driving a lower endless conveyor and the lower endless conveyor supported thereupon, a set of upper transversely extending shafts for supporting and driving an upper endless conveyor and the upper endless conveyor supported thereupon, said upper conveyor being shorter than the lower conveyor and being arranged so that the lower cord thereof is parallel to and directly above the forward or delivery end of the upper cord of the lower conveyor whereby there is provided a table section at and by the rear upper portion of the lower conveyor and upon which table section material to be sliced is received preparatory to its being conveyed and fed longitudinally between, and by the joint action of, the upper and lower conveyors to a cutter at the forward part of the machine, a longitudinally extending cutter-carrying shaft which is located over said conveyors, a slicing cutter carried by said shaft at the forward end thereof and having the cutting section thereof transversely movable across the longitudinal path of travel of the material fed thereto by said conveyors, a transversely extending intermediate shaft and gearing whereby the latter is driven from said longitudinally extending cutter-carrying shaft, means whereby said transversely extending intermediate shaft drives said upper conveyor, means whereby said transversely extending intermediate shaft drives said lower conveyor, and suitable bearings on said frame in which the several shafts are rotatably mounted, said slicing machine having a hollow, stationary throat member between and cooperatively related with the forward ends of the conveyor and with the knife and serving to guide the material to be sliced to the knife and for supporting the material while being sliced.
2. A slicing machine as defined in the claim last preceding in which there is a motor carried by the frame, which motor is located over said conveyors and has the rotor thereof connected so as to drive the longitudinally extending cutter-carrying shaft.

Signed at Chicago, Illinois, this 27th day of September, A. D. 1930.

NICKOLAS JOSEPH DZIEDZIC.
HARRY HENRY McKEE.
